UNITED STATES PATENT OFFICE.

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS.

WEFT DETECTOR CONTROLLED BY PATTERN MECHANISM.

Application filed March 19, 1925. Serial No. 16,780.

This invention relates to improvements in weft detectors for drop box looms and more particularly to the type of detector which is rendered more sensitive when operating with fine yarn than when cooperating with coarse yarn.

In box looms where two or more shuttles are employed it is occasionally desirable to supply one of the shuttles with very fine yarn to weave a fancy stripe and to supply the other shuttles with relatively coarse yarn. Under such conditions a detector of the usual type capable of but one adjustment is not well suited to detect the condition of yarn on all the bobbins inasmuch as it would leave too much fine yarn at the time of indication of weft exhaustion if it were set so as to prevent complete exhaustion of the coarse yarn. In order to render the detector variably sensitive I have provided means for changing the adjustment of the detecting parts to the end that the adjustments may be finer for fine yarn than is the case with the coarse yarn. When applying this principle to detectors of the type having a yarn impinging member and a lay actuated member it is desirable that the change in adjustment take place before the lay actuated member is engaged by the controlling portion of the lay.

In my co-pending applications Serial No. 758,905 and No. 13,585 I have shown a detector of the type specified having a detector member to be engaged by a variable member carried on the lay. In the operation of this type of detector the lay actuated member is engaged on each forward beat of the lay whether the shuttle be on the detector side of the loom or on the box side of the loom and it is also true in drop box looms that the boxes change in the interval between protection and picking so that they are in motion when the lay is in its forward position. This change occurs while the lay actuated part of the detector is in engagement with the controller on the lay. This is an undesirable condition inasmuch as undue wearing results and in order to overcome this defect I have provided mechanism whereby the indication for the lay carried controller for the lay actuated member of the detector is actuated in advance of the movement of the boxes so that the controlling member on the lay moves to its

new position before coming in contact with the detector.

With the general object therefor of preventing movement of the detector controller at the time when the same is engaged by the lay actuated member, and other objects which will appear as the description proceeds, my invention resides in the combination and arrangement of parts hereinafter described and set forth in the claims.

In the accompanying drawings wherein I have shown a convenient embodiment of my invention,

Fig. 1 is a front elevation of a loom having my invention applied thereto,

Fig. 2 is an end elevation of the loom looking in the direction of arrow 2, Fig. 1,

Fig. 3 is an enlarged fragmentary top plan view of a portion of the detector,

Fig. 4 is an enlarged end elevation of the controller slide looking in the direction of arrow 4, Fig. 2,

Fig. 5 shows a horizontal section on line 5-5 of Fig. 4 looking in the direction of the arrows,

Fig. 6 is a detail of the eccentric control member on the lay set for coarse yarn, and

Fig. 7 is a view similar to Fig. 6 but set for fine yarn.

To illustrate my invention I have shown the same as connected to portions of the well-known Knowles head but it is to be understood that my invention is not limited to use with this type of pattern mechanism but can be used wherever a pattern surface moves in advance of the boxes which it controls.

Referring more particularly to Figs. 1 and 2 it will be seen that I have provided a loom frame 10 and a lay 11 having drop boxes 12 on the left hand side thereof and a single box 13 on the right hand end thereof. Said boxes 12 are supported by box rod 14 which is raised by chain 15 and pushed down by spring 16. The chain 15 is of the usual form and is operated by connections with the well-known Knowles head indicated at K. It is to be understood that the chain 15 is raised or lowered in accordance with the demands of the pattern chain to vary the position of the active box.

The head motion includes in its construction the frame 17 on which are pivotally mounted as at 18 a plurality of vibrator

levers 19 each of which carries the usual vibrator gear indicated at 20. Upper and lower driving cylinders 21 and 22, respectively, are rotated so as to give the vibrator gear opposite movements, the position of the vibrator levers 19 being determined by the pattern chain 23. The pattern chain is moved by mechanism not shown and the vibrators are raised and lowered according to the sequence of rolls and sinkers on the pattern chain. Upstanding from the frame 17 is a horn 24 to the upper end of which is pivotally connected a lever 25 to the outer end of which is adjustably secured a stud 26. A rod head 27 mounted on the stud 26 is pivotally connected by a link 28 to a floating lever 29 pivotally connected at the central portion thereof as at 30 to a shorter lever 31. Said lever 31 is pivotally connected as at 32 at the central portion thereof to the horn 24 and said levers 29 and 31 are laterally spaced as indicated in Fig. 2 so that the floating lever engages the front vibrator 19 and the shorter lever 31 engages the rear vibrator, each of said levers being raised when the corresponding vibrator is raised and being lowered by mechanism to be described hereinafter when the vibrators are depressed. It is to be understood that the pattern chain 23 which moves around shaft 33 will raise the vibrator levers and consequently the levers 29 and 31 before the boxes 12 start to move. This part of the mechanism may be similar to that shown in Patent No. 1,205,792 to Ryon.

The remainder of the construction shown herein is substantially the same as that shown in my aforesaid application and comprises the detector and the lay carried controller for the lay actuated member of the detector. The detector includes a slide 34, Fig. 3, which is movable forwardly under influence of the lay and has pivoted thereto as at 35 a yarn impinging detector 36 held in position by the hooked end 37 of a rod 38 and acted upon to have a counter-clockwise movement by a rod 39 at the time of indication. A screw 40 shown in dotted lines in Fig. 3 is adjustably mounted in a depending arm 41 rigid with the slide 34.

The screw 41 is positioned for engagement with an eccentric 42 mounted on the lay and movable angularly to engage the screw at different times in the forward movement of the lay depending upon which shuttle is active. Said eccentric has an elongated gudgeon 43 extending to the right and a second gudgeon 44 extending in the opposite direction, said gudgeons being received by bearings 45 having caps 46. The gudgeon 44 has adjustably secured thereto an arm 47 the forward end of which is connected to a cord 48 extending from said arm under a sheave 49 loosely mounted on rocker shaft 50 about which the lay moves. The

cord extends from the sheave 49 to the lower end of a lever 51 which is pivotally mounted upon a fixed stud 52 and has an upwardly extending arm 53 to which is secured a stud 54 as shown in Figs. 4 and 5. Secured to the loom frame is a stand 55 in which is guided a slide 56 held therein by plates 57. Said slide has an offset slot 58 therein into which the stud 54 projects. A spring 59 is interposed between the lower end of the slide and a fixed part of the loom and tends normally to hold the slide down. The upper end of the slide is connected as by a cord 60 to the previously described lever 25. The gudgeon 43 of the eccentric 42 has secured thereto a collar 61 between which and the adjacent bearing 45 is a torsion spring 62 which acts to raise the lever 47.

As shown in Figs. 2 and 6 the parts are set to cooperate with coarse yarn, the relation of the arm 47 and the eccentric 42 being that shown in Fig. 6 where it will be seen that the center of the eccentric is above the axis of the gudgeon 43 to cause the screw 40 to engage the eccentric at a comparatively early time in the forward beat of the lay. Since the screw engages the eccentric at a point above the gudgeon 43 the cord 48 will be held taut. When the boxes change and fine yarn becomes active the lever 25 will be lowered to the dotted line position shown in Fig. 1 which will permit spring 59 to move the slide 56 downwardly and move lever 51 to the dotted line position shown in Fig. 2. Spring 62 will move the eccentric 100 and arm 47 from the position shown in Fig. 6 to that shown in Fig. 7, the arm 47 being raised and the center of the eccentric being substantially in horizontal alignment with the axis of the gudgeon 43. As the lay advances the eccentric will engage the screw 40 at a comparatively late time in the beat of the lay. Because of the arrangement of the centers of the eccentric and the gudgeon there will be no tendency to turn said eccentric.

As previously stated the pattern mechanism of a loom which determines the sequence in which the shuttles shall become active operates necessarily in advance of the 115 shuttles themselves and in the usual type of loom the box indicating mechanism comes to rest some time prior to protection. By the connection shown herein the eccentric 42 will therefore be at rest during the latter 120 part of the forward beat of the lay and will not be given an angular movement while the lay is on front center. For this reason there will be no relative movement of the eccentric and the screw 40 while these two members 125 are in contact with each other as is the case in my previously mentioned applications.

From the foregoing it will be seen that I have provided a weft detector having a member to be engaged by a lay carried con-

troller and capable of assuming varying degrees of sensitiveness under control of the pattern mechanism of the loom so that the change from one degree to another will be accomplished before the detector member is engaged by the lay carried controller.

Having thus described my invention it will be apparent that changes and modifications may be made therein by those skilled 10 in the art without departing from the spirit and scope of the invention and I do not wish to be limited to the details herein disclosed, but what I claim is:

1. In a weft detector for looms having 15 a plurality of shifting shuttle boxes and shuttles carrying wefts of different sizes, pattern mechanism to determine which of said shuttle boxes shall move to active position, a detector capable of assuming different 20 adjusted positions, and connections between the pattern mechanism and said detector to effect the change from one adjusted position to another prior to the movement of the boxes.

2. In a weft detector for box looms having 25 a plurality of shifting shuttle boxes and shuttles carrying wefts of different sizes, a detector capable of assuming different adjusting positions, a lay, a controller for the 30 detector on the lay, pattern mechanism, and connections from the pattern mechanism to the controller to complete the change from one adjusted position to another position before the latter reaches the limit of its forward movement.

3. In a weft detector for looms having a 35 plurality of shifting shuttle boxes and shuttles supplied with yarns of different sizes, pattern mechanism to determine which 40 of said shuttle boxes shall become active, a detector capable of assuming different adjusted positions, a lay, a lay carried controller to cooperate with the detector, and connections from the pattern mechanism to 45 the controller to effect a change in the adjustment of said detector before the controller moves to cooperating position with respect to the detector.

4. In a detector for drop box looms having 50 a plurality of shuttle boxes and shuttles any one of which may become active, said

shuttles carrying yarns of varying sizes, a weft detector capable of assuming a plurality of adjusted positions depending upon which shuttle box is active, pattern mechanism, and connections from the pattern mechanism to the detector to effect a change in the latter from one position to another, said connections being independent of the boxes and acting in advance of the movement of said boxes.

5. In a detector for box looms having a plurality of shifting shuttle boxes and shuttles any one of which may become active, 55 said shuttles carrying yarns of different sizes, a yarn impinging member for the detector, a lay, a lay actuated member for the detector, and a controller on the lay to have contact with the lay actuated member of the detector, pattern mechanism having a 70 movement while the lay actuated member is out of contact with the controller, and connections from the pattern mechanism to the controller to move said controller to different positions dependent upon the position of 75 the shuttle boxes, and to give said controller its complete motion before the lay reaches the forward limit of its movement.

6. In a detector for box looms having a plurality of shifting shuttle boxes and 80 shuttles carrying yarns of different sizes, a lay, a yarn impinging member for the detector, a lay actuated member for the detector comprising an element controlling the 85 yarn impinging member and a second element carried by the lay to contact with the first named element at different times in the forward movement of the lay, pattern mechanism having a movement while the lay actuated member is out of contact with the controller, and connections from the pattern mechanism to the lay actuated member to effect a relative change between the elements before said elements contact with each other, said connections and pattern 90 mechanism effecting the change dependent upon the position of the shifting shuttle boxes.

In testimony whereof I have hereunto affixed my signature.

WALTER H. WAKEFIELD.
